RAZOR BLADE MAGAZINE

Sidney H. Benjamin, Milwaukee, Wis.

Application July 1, 1941, Serial No. 400,586

2 Claims. (Cl. 206—16)

My invention relates to safety razor blade magazines and refers particularly to safety razor blade magazines adapted for co-operation with magazine holders and safety razors for the withdrawal of a single blade from said magazine while the remainder of the blades are retained therein.

The particular devices of my invention illustrated in the accompanying drawing comprise safety blade magazines of particular constructions to adapt them for co-ordinated employment with a magazine holder for use with safety razors, whereby a single blade may be withdrawn from the magazine while the remainder of a stack of blades within the magazine will be retained therein.

In devices of this character the blade magazine is moved inwardly into a holder, the magazine having extensions adapted to move within runways, or channels within the holder, in order that the magazine may be placed and retained in proper position for application to a safety razor having means whereby the movement of the holder and of the magazine will withdraw a blade from the magazine and place it properly upon the guard of the razor.

It is, therefore, necessary that the magazines possess such physical formations to thus co-operate with both the magazine holder and the safety razor head elements, in order to produce the desired result.

The devices of my invention, therefore, are directed to safety blade magazines of the forms shown in the accompanying drawing, in which similar parts are designated by similar numerals.

Figure 1 is a perspective view of the blade magazine of my invention.

Figure 2 is a bottom view of Figure 1.

Figure 3 is a section through the line 3—3 of Figure 1.

Figure 4 is a section through the lines 4—4 of Figure 1.

Figure 5 is a top plan view of the spring of Figure 1.

Figure 6 is a top plan view of a razor blade for which my magazine of Figures 1 to 5 is adapted.

Figure 7 is a top plan view of a modified form of my magazine partly broken away for purposes of explanation.

Figure 8 is a section through the lines 8—8 of Figure 7.

The safety razor blade magazine shown in Figures 1 to 5 inclusive comprises a casing having the top member 10 having the centrally positioned recess 11. Each side of the top 10 is extended outwardly and then inwardly forming the out-

wardly extended guide member 12, thence downwardly forming the wall 13 and thence inwardly forming a bottom member 14. It will be noted that the two bottom members 14, 14 are spaced from each other.

Two blade retaining studs 15, 15 extend downwardly from the top 10 and are affixed thereto by rivets 16, 16. These studs are adapted to pass through openings 17, 17 of razor blades 18, 18 and are of such lengths that they do not pass through the openings of the outermost blade 18a. It will thus be seen that the outermost blade 18a can be withdrawn from the magazine while the studs 15, 15 will retain the other blades within the magazine.

A spring 19, having openings 20, 20 for reception of the studs 15, 15 and a recess 21 corresponding to the recess 11 of the top 10, is so positioned that it will constantly press the stack of blades toward the bottom members 14, 14 with the outermost blade 18a abutting upon these bottom members.

For convenience in withdrawing the magazine from the holder, an extended portion 22 is cut out from a side member 13.

The end cross-section of this device is such that the members 12, 13 and 14 correspond to the cross-section of a magazine holder, thus allowing these members of the magazine to co-operate with the holder construction and allow of the proper positioning of the magazine within the magazine holder.

The blade magazine shown in Figures 7 and 8 is adapted for use with wider blades 30 having four openings 31, 31 therein and a deeper recess 32 extending inwardly beyond the center of the blades.

In this form of my magazine the top 10 has a longer recess 33 corresponding to the recess 32 of the blade, and it has four blades positioning studs 15, 15 to accommodate the four openings in the blade instead of two as shown in the former drawings and two short recesses 34, 34.

It is to be noted that the end cross-section of the device of Figures 7 and 8 is the same as the device of Figures 1 to 5, as this formation is an element of my invention.

I do not limit myself to the particular size of the elements shown, as these must necessarily correspond with the size of the co-operating elements of the magazine holder with which the magazine is employed.

What I claim is:

1. A safety blade magazine capable of being removably carried within a magazine holder and

adapted for containing a plurality of stacked safety razor blades comprising a top member having an inwardly extended recess from its one end, a bottom member having a longitudinal opening extending from one end thereof, two side members, an opening in one end of the device allowing the passage of a blade therethrough, at least one blade retaining stud extending from said top member toward said bottom member and spaced from said bottom member the thickness of a razor blade, and a resilient member capable of normal resilient abutment upon said bottom member, the upper longitudinal edges of said device being extended outwardly from the sides thereof.

2. A safety blade magazine capable of being removably carried within a magazine holder and

adapted for containing a plurality of stacked safety razor blades comprising a top member having an inwardly extended recess from its one end, a bottom member having a longitudinal opening extending from one end thereof, two side members, an opening in one end of the device allowing the passage of a blade therethrough, a plurality of blade retaining members extending from said top member toward said bottom member and spaced from said bottom member the thickness of a razor blade, and a resilient member capable of normal resilient abutment upon said bottom member, the upper longitudinal edges of said device being extended outwardly from the sides thereof.

SIDNEY H. BENJAMIN.
